United States Patent Office

Des. 221,853

Patented Sept. 14, 1971

221,853

HEAT RADIATION PLATE

Keiichi Kimura, 2-304 Osakabe, Yaoshi,
Osakafu, Japan

Filed Dec. 31, 1969, Ser. No. 20,722

Term of patent 14 years

Int. Cl. D23—03

U.S. Cl. D23—127

Fig 4

Fig 5

Fig 1

Fig 6

Fig 2

Fig 3

FIG. 1 is a plan view of a heat radiation plate showing my new design;

FIG. 2 is a plan view of the reverse side thereof;

FIG. 3 is a cross-sectional view taken on line 3—3 of **FIG. 1**;

FIG. 4 is an end elevational view thereof;

FIG. 5 is a left hand side elevational view thereof;

FIG. 6 is a right hand side elevational view thereof;

FIG. 7 is a perspective view thereof.

The stippling shown on the heat radiation plate in **FIG. 7** is omitted in FIGS. 1 through 6 for convenience of illustration.

I claim:

The ornamental design for a heat radiation plate, as shown.
